UNITED STATES PATENT OFFICE.

MARTHA E. BARBOUR, OF SCRANTON, PENNSYLVANIA.

ASH-SIFTER.

SPECIFICATION forming part of Letters Patent No. 691,522, dated January 21, 1902.

Application filed April 20, 1901. Serial No. 56,698. (No model.)

To all whom it may concern:

Be it known that I, MARTHA E. BARBOUR, a citizen of the United States, residing at Scranton, in the county of Lackawanna, State of Pennsylvania, have invented certain new and useful Improvements in Ash-Sifters, of which the following is a specification.

This invention comprises an improved attachment for ash-sifters whereby the sifter may be readily supported over a barrel, can, or other ash-receiver during the sifting operation.

In the accompanying drawings, which illustrate my invention, Figure 1 is a plan view of an ash-sifter having my improvements attached. Fig. 2 is a side view of the same; and Fig. 3 is a perspective view of a portion of a barrel, illustrating the manner in which the ash-sifter is supported thereon.

Referring to the drawings, A indicates an ash-sifter to which my improvements are attached. This sifter, as shown in the drawings, consists of a circular sheet-metal pan formed with suitable perforations 1, to permit the ashes to pass through, and having at one side a handle 2; but the sifter may be otherwise designed and may be constructed of any suitable material.

My invention comprises the attachment hereinafter described for pivotally supporting and guiding the sifter when the latter is placed across the top of an ash-receiver.

In carrying out my invention I secure centrally to the under side of the pan a plate 3, having thereon a stud or pivot pin 4 and an annular shoulder 5 at the base of the stud. To this stud is connected a support comprising the two radial arms 6 and 7, formed, preferably, from a single rod, said rod having a part 8 at the junction of the two arms bent around the stud or pivot-pin 4, and the outer ends of the arms having portions 9, extending upwardly above the upper edge 10 of the pan, and hooks 11, which are adapted to fit over the upper edge of the ash-receiver. As shown in Fig. 2, the radial arms have upwardly-offset portions 12, which guide and support the pan at two points near its periphery. The hooked portions 11 are bent inwardly toward the vertical parts 9, as shown at 13, thus forming stops which engage the top of the ash-receiver. The ends 14 of the hooks,

below the stops 13, extend downward on the outside of the receiver B, as shown in Fig. 3. The annular part 8 of the support is secured around the pivot-pin by a brace-rod 15, the inner end 16 of which is wrapped around the radial arms of the support at their junction with the part 8. This rod, as shown, is downwardly inclined, and its outer end 17 is adapted to rest against the inner wall of the ash-receiver when the sifter is in place, as shown in Fig. 3. The rod 15 thus braces the sifter and binds the collar or annular part 8 of the support around the pivot-pin. The two arms of the support are connected by a curved connecting-rod 18, the ends of which are secured to the upright portions 9 of the arms. This bar extends parallel with the edge of the pan above and in contact with the handle 2, the latter being connected to the pan between the arms of the support by a downwardly-bent portion 19.

In operation the sifter is placed within the ash-receiver, as shown in Fig. 3, with the hook portions extending over the edge of the receiver and the end 17 of the brace against its inner wall. The sifter will thus be pivotally supported within the receiver and the ashes may be sifted by oscillating the handle 2 in an obvious manner. The offset portions 12 of the radial arms support and guide the sifter at two points on either side of the handle. Any tendency of the sifter to tilt toward the side away from the handle due to heavy loading on that side will be counteracted by the rod 18, which extends over the handle. This bar, it will be seen, effectually prevents the sifter from tilting forward and forms a guide for the handle as well as a brace for the arms of the support.

It will be evident that the attachment may be applied to sifters of various designs and that it may be suited to receivers of different forms with slight variation in the arrangement of the parts of the support. I do not, therefore, wish to limit myself to the exact construction shown in the drawings.

Having described my invention, what I claim, and desire to secure by Letters Patent, is—

1. The combination with a sifting-pan having a suitable handle, of a support pivotally secured to the under side of said pan, said

support comprising two radially-extending arms having hooked ends adapted to extend over the upper edges of an ash-receiver, and a rod connected to said hooked ends and overlying the handle.

2. The combination with a sifting-pan having a suitable handle, of a support pivotally secured to the under side of said pan, said support comprising two radially-extending arms having hooked ends adapted to extend over the upper edges of an ash-receiver, and a brace connected to said support at or near its pivotal point and adapted to engage the inner wall of the receiver.
- 15 3. The combination with a sifting-pan having a suitable handle, of a support pivotally secured to the under side of said pan, said support comprising two radially-extending arms having hooked ends adapted to extend over the upper edges of an ash-receiver, a brace connected to said support and adapted to engage the inner wall of the receiver, and a rod connected to said hooked ends and overlying the handle.
- 20 4. The combination with a sifting-pan hav-

ing a stud projecting from its under side, of a support comprising a rod bent around said stud to form a collar and having two radial arms provided with hooked ends adapted to rest upon the edges of an ash-receiver, and 30 a brace one end of which is secured to said arms adjacent to the collar, the opposite end of the brace being adapted to engage the inner wall of the ash-receiver.

5. The combination with an ash-sifter, of 35 a support pivotally secured to the under side of said sifter, said support comprising two arms extending radially beneath the sifter and having upwardly-offset portions adapted to support and guide the edge of the sifter 40 and hooked ends adapted to engage the edges of an ash-receiver, and a brace secured to said support and adapted to engage the inner wall of the receiver.

In testimony whereof I affix my signature 45 in presence of two witnesses.

MARTHA E. BARBOUR.
